UNITED STATES PATENT OFFICE.

WILLIAM HOMER PIGG, OF GRANNIS, ARKANSAS.

GEARING.

1,188,317.

Specification of Letters Patent. Patented June 20, 1916.

Application filed March 21, 1914. Serial No. 826,352.

To all whom it may concern:

Be it known that I, WILLIAM HOMER PIGG, a citizen of the United States, residing at Grannis, in the county of Polk and State of Arkansas, have invented new and useful Improvements in Gearing, of which the following is a specification.

This invention is an improved churn and consists in the construction, combination 10 and arrangement of devices hereinafter described and claimed.

One object of the invention is to effect improvements in the construction of the churn dasher.

15 Another object of the invention is to provide improved means for operating the churn dasher.

Another object is to effect improvements in the support for the dasher and the dasher 20 operating means.

Another object is to provide an improved churn which is cheap and simple, is strong and durable and which may be readily assembled and disassembled so that the churn 25 and all of its parts may be kept clean and in working order.

In the accompanying drawings: Figure 1 is an elevation of a churn constructed in accordance with my invention the churn 30 body or vessel being indicated in dotted lines. Fig. 2 is a vertical sectional view of the same. Fig. 3 is a horizontal sectional view of the same on the plane indicated by the line *a—a* of Fig. 2. Fig. 4 is a detail 35 horizontal sectional view of the same on the plane indicated by the line *b—b* of Fig. 2. Fig. 5 is a similar view on the plane indicated by the line *c—c* of Fig. 2. Fig. 6 is a detail vertical sectional view through the 40 dasher, on the plane indicated by the line *d—d* of Fig. 2.

In the embodiment of my invention I provide a platform 1 on which a churn body or vessel 2 of any suitable size, shape and 45 construction may be arranged. This vessel or any other form of horizontally-rotatable member is provided with a shaft-receiving socket. At one end of the base is a vertical hollow standard 3. A vertically adjustable support 4 is provided which has a vertical arm 5 that is slidably arranged in the standard 3. The said standard has threaded openings in one side which are engaged by set screws 6. Said set screws enable the support 4 to be secured at any 55 desired adjusted position.

The support 4 has a horizontal upper arm 7 from which depends a substantially rectangular hanger 8 that comprises an outer side member 9, a lower member 10 and an inner member 11. A T shaped bearing 12 is secured to the outer member 9 of the hanger and a horizontally arranged shaft 13 is mounted in bearing openings in the member 11 and vertical arm 5 and has its inner 60 end stepped in a bearing in one side of the T shaped bearing 12. A beveled gear 14 is secured on the said shaft 13. At the outer end of the said shaft is a detachable crank handle 15 by means of which said shaft, together with its gear 14 may be rotated.

The dasher 16 has an outer rectangular frame 17 which is provided in opposite sides with horizontally arranged blades 18—19. The said blades are inclined transversely and 75 the blades 19 are arranged at right angles to the blades 18. At the upper side of the frame, at its center is a tubular shaft 20 which extends up through a bearing opening in the member 10 of the hanger 8 and is 80 provided with a beveled gear 21 which engages the lower side of the gear 14. This shaft 22 is received in the socket formed at the lower end of the churn, vessel or other horizontally-rotatable member.

85 A shaft 22 passes through the tubular shaft 20 and its lower portion has bearings in the upper and lower sides of the dasher frame 16. From opposite sides of this shaft project blades 23—24 which are arranged 90 in the horizontal spaces between the blades 18—19 and are also inclined in reverse directions, the blades 23 being substantially at right angles to the blades 24. The upper portion extends through the bearing 12 and 95 is mounted therein and is provided with a beveled gear 25 which engages the upper side of the gear 14.

From the foregoing description it will be understood that when the shaft 13 is revolved the gears 14, 21 and 25 will cause the tubular shaft 20 and the shaft 22 to rotate simultaneously in opposite directions so that the dasher frame with its blades 18—19 will revolve in one direction and the dasher 105 blades of the shaft 22 will be simultaneously revolved in the opposite direction. Owing to the inclined position of the dasher blades, transversely, and the reverse arrangement of the said blades, both of the dasher frame 110 and of the dasher shaft the cream will be forced both upwardly and downwardly as

well as whirled and thoroughly agitated by the dasher blades and hence the cream will be converted into butter, in a very short time. Moreover splashing of the cream out 5 of the vessel or body of the churn will be avoided. The dasher may be raised or lowered in the churn, vessel or body by properly adjusting the arm 5 in the standard 3 according to the depth of the body of 10 cream to be churned.

Having thus described my invention, I claim:

In a device of the class described, in combination a base board, an upright tubular bearing mounted upon said base board, a rod telescoping in said bearing, a horizontally rotatable member carried upon said base board, and having a shaft-receiving socket, a vertical shaft projecting into said 15 socket, a rectangular frame supported upon said member, said shaft projecting through 20 said frame, a rectangular hanger supported upon said frame, a sleeve integrally formed 25 upon the top of said first-named rectangular frame and projecting through said tubular boss to be reinforced thereby, said shaft projecting through said sleeve, a gear wheel secured to the upper end of said shaft, a gear wheel secured to the upper end of said 30 sleeve, a gear wheel meshing with said first gear wheel, a shaft passing through said rod and the rectangular hanger thereon upon which the last-named gear is secured, 35 means for turning said shaft.

In testimony whereof I affix my signature in presence of two witnesses.

WILLIAM HOMER PIGG.
